UNITED STATES PATENT OFFICE

1,921,617

WATERLESS GASOMETER

Georg v. Hanfstengel, Nurnberg, Germany, assignor to Maschinenfabrik Augsburg-Nurnberg A.-G., Nurnberg, Germany, a Corporation of Germany

Application December 28, 1928, Serial No. 329,059,
and in Germany January 4, 1928

2 Claims. (Cl. 48—176)

My invention relates to waterless gasometers adapted for use in storing large quantities of gas in the open under exposure to the elements (i.e., wind pressure, snow, etc.), and has for its object to provide a sealing means for gasometers of the disc type to seal in an efficient and reliable manner the clearance gap between the vertically movable closure disc and the inner faces of the walls of the gasometer so as to prevent leakage of gas through such gap. With this end in view, my novel sealing means is composed of a closed metallic ring, which is of uniform cross-section and of uniform strength throughout, so that it will expand and contract uniformly throughout its entire circumference, and is rendered pliable so as to conform readily to irregularities in the container wall by subjecting the same to a more or less uniform pressure throughout its entire circumference and by so proportioning it that its elastic expansion under the influence of said pressure supplies the necessary pliability.

In the accompanying drawing which illustrates by way of example a form of my invention as applied to a gasometer, without, however, defining its limits, Fig. 1 shows a vertical section through a part of the gasometer; Fig. 2 is a diagrammatic view on a smaller scale illustrating the general principle of my invention; and Fig. 3 is a view similar to Fig. 1 but shows a slightly modified construction wherein the use of a packing element is dispensed with.

The gasometer shell is indicated at *a* and is reinforced in the well-known manner by the posts *b*. A closure disc *c* is arranged inside of the shell and serves as the upper closure therefor. According to the invention, a vertical ring *f* surrounds the edge *d* of the disc *c* and is attached to said edge by means of a connection or strip *e* composed of textile material, leather or other suitable material. This ring *f* may be provided with packing or sealing bodies *g* made of felt or similar material, and in order to insure a more nearly perfect seal the annular trough between the disc *c* and the wall *a* is filled with a liquid which, because of its lubricating action, serves at the same time to reduce the resistance to the movement of the disc.

The ring *f* and its packing *g* are pressed toward the interior face of the container wall by means of a large number of weighted levers *h* which are arranged upon the disc *c* about the circumference of the latter, the levers *h* being acted upon by weights *i*, of which only one is shown.

In order to permit the ring *f* to conform

readily to all irregularities of the inner surface of the shell of the container, it is made of uniform cross-section and uniform strength of material throughout, and its dimensions are so proportioned, relative to such wall, that it is expanded uniformly by pressure exerted outwardly thereagainst by the weighted levers, and to such an extent as to fit closely or to cause a packing ring associated therewith to fit closely against the entire wall of the container at all positions of the ring. In other words, the ring is expanded by the pressure acting against it and is normally held in an expanded condition, so that it will readily yield to forces tending to contract it or expand further wherever necessary.

This expansion is within the elastic limit of the material of which the ring is composed and maintains the ring in a constant state of tension. This condition of elastic extension or expansion of the ring produces the highly desirable result that when the ring encounters an inwardly extending irregularity in the inner surface of the shell the ring will not bulge inwardly and spring away from such wall and create a gap, as would be the case if the ring were initially constructed so as to fit closely against the shell, but, on the contrary, the ring will contract circumferentially. In this way, variations in the internal diameter of the shell will be followed by further expansion or by contraction of the circumference of the ring, so that the latter will conform very closely to the inner contour of the shell and thereby produce an efficient and reliable seal with the shell.

While I prefer to retain the ring at all times in a condition of partial expansion, I may so proportion my ring, relatively to the gasometer wall, that no expansion is necessary initially to maintain a tight fit. In that case the pressure of the weighted levers will cause the ring to expand wherever expansion is necessary to adjust itself to irregularities, whereas, on the other hand, the natural elasticity of the ring will permit it to contract wherever contraction is necessary to adjust to irregularities.

The number of weighted levers *h* to be employed will obviously depend upon the size of the gasometer, the magnitude of the weights *i* (or the strength of the springs if such are employed in place of weights as shown in my U. S. Patent No. 1,481,099), the extent to which the material of the ring can be stretched without producing a permanent set, and the degree of pressure which the ring is to exert upon the

inner wall of the gasometer, such degree of pressure depending largely upon the pressure of the gas within the gasometer. Preferably I use, for expanding a ring adapted to fit a gasometer of 50 meters diameter, a weighted lever for every 40 cm to 50 cm of circumference, or somewhat in excess of 300 levers altogether. The unit pressure against the ring which is required to produce a definite expansion can be readily ascertained. A simple calculation shows for example that in a gasometer of about 50 meters diameter and at a pressure of 0.1 kg/cm² an iron ring of 2.5 mm thickness possesses such an elastic extensibility that it can yield at any point about 1 cm in a diametral direction, which is completely sufficient even for rather large irregularities.

The loading of the ring can also be effected, in place of the levers and weights, by means of liquid or air pressure or other suitable means, such as springs, without in any way departing from the principle of the invention. In my claims I refer to such various means as "means for exerting substantially uniform pressure against the circumferential surface of said ring sufficient to press the same against the inner surface of the gasometer shell." The ring itself may be composed of strips of sheet metal which are so joined in a circumferential direction by welding, riveting or otherwise, that a substantially uniform ring, referred to in my claims as an "integral" ring, having the above-described properties is produced. The ring may be composed of iron, copper or any other suitable metallic material provided that it has the necessary strength and elasticity. Copper and also aluminum appear to be especially suitable because of their low moduli of elasticity.

From Fig. 2 it will be clear that the ring *f* is loaded from the interior thereof throughout its entire circumference. The small arrows indicate diagrammatically the direction of the pressure exerted by the levers *h* and weights *i* against the ring *f* but not, of course, the number of levers to be employed. It can be readily seen that the elastic elongation or enlargement of the diameter of the ring under the action of the weighted levers permits the ring to follow closely whatever irregularities of the inner shell surface it may encounter.

The packing or sealing bodies *g* are not essential for the proper action of the ring *f* and may for that reason be omitted and then the ring alone is sufficient as a sealing means, the wall of the gasometer sliding thereon as shown in Fig. 3. The introduction of the sealing or lubri-

cating means into the gap between the disc and the shell can be accomplished in any well-known manner should it be desired to dispense with the filling of the annular trough with sealing liquid. There may also be employed, for example, a series of superposed sealing bodies, the space between them being filled with the lubricating or sealing means. Of course, if desired, such special sealing means may be dispensed with.

Variations may be resorted to within the scope of the claims without departing from the spirit of the invention. It is obvious that my sealing ring may be used as a sealing element in connection with closures other than those of disc gasometers or other than disc gasometers of annular cross-section, for instance, gasometers of polygonal cross-section; and further that such ring need not be circular but may assume the form of the container to which it is applied. I therefore wish it to be understood that where in the claims I employ the term "ring" I include thereby all closed rings or loops whether curvilinear or polygonal in outline.

I claim:

1. In a waterless gasometer adapted for use in storing large quantities of gas in the open under exposure to the elements, and having a shell of substantially circular cross-section and a disc adapted to act as a closure member, a sealing element connected with such disc, which element includes an integral metal ring of substantially uniform cross-section and strength throughout, and therefore capable of uniform circumferential expansion and contraction throughout substantially the whole body of said ring, and means for exerting substantially uniform pressure against the circumferential surface of said ring sufficient to press the same against the inner surface of the gasometer shell and against the inner resistance of the ring, the relation between the external diameter of the ring and the internal diameter of the gasometer being such that said pressure means produces no permanent set in said ring.

2. A structure as set forth in claim 1 in which the metal ring is of smaller external diameter under the normal conditions of operation than the internal diameter of the gasometer but of a diameter sufficiently large to permit the means for exerting substantially uniform pressure thereagainst to press the same into contact with the inner surface of the gasometer shell, whereby such ring is under tension when acting as a sealing element.

GEORG v. HANFFSTENGEL.
